UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

HAY-CARRIER.

1,101,170.

Specification of Letters Patent. Patented June 23, 1914.

Application filed November 11, 1913. Serial No. 800,367.

To all whom it may concern:

Be it known that I, HENRY L. FERRIS, a citizen of the United States, residing at Harvard, in the county of McHenry and 5 State of Illinois, have invented a new and useful Improvement in Hay-Carriers, of which the following is a specification.

My invention relates to certain new and 10 useful improvements in hay carriers, and is fully described and explained in the specification and shown in the accompanying drawings, in which—

Figure 1 is a side elevation of my improved hay-carrier; Fig. 2 is an end view, 15 taken from the left in Fig. 1, but showing the device rigged as a cross-draft carrier; Fig. 3 is a section on the line 3 of Fig. 1; Fig. 4 is a longitudinal section through the movable sheave housing, and Fig. 5 is a top 20 plan of the rope guide.

Referring to the drawings, 6 is a track provided with a trip-block 7 on which runs a carriage 8 to which is swiveled a frame 9 capable of being locked in position by means 25 of a latch 10. The arrangement is such that the frame can be turned around 180° to operate in either direction on the track, in accordance with common practice. The frame has, at its front end, a guide sheave 11 over 30 which passes a rope 12. The rope is led back between a clamping member 13 on its upper side and the forward operative end of a clamping lever 15 on its lower side, the clamping member and lever coöperating as 35 shown in my Patent No. 826,095, so that no detailed illustration or description of the construction and operation of the parts is here attempted, except to state that as the rear end of the clamping member 15 falls, 40 under the weight of the load when released as hereinafter set forth, the rope is clamped between the two parts. A further reason for omitting detailed description of this clamping operation is in that no novelty is 45 claimed therefor, and any common locking arrangement can be adopted. The rear end of the locking lever 15 has a pin 16 running in a slot 17 in a trip-member 18 pivoted to the frame at 19.

50 22 is a dog, one end 21 of which engages the trip-member 18 to hold it in elevated position and the other end 20 of which is pivoted to a link 23 running down to a lever 24 pivoted to the frame.

55 The general operation can now be readily

understood, it being assumed that the weight of the load is carried by the locking lever 15, although the particular manner of supporting the load involves novelty which will hereinafter be set forth. When the 60 trip-member 18 engages the trip-block, as shown in Fig. 1, the dog also engages the trip-member to hold it up and the sling-pulleys are thus free to be raised and lowered, the rope running free. When 65 the dog is rotated on its pivot, either by engagement of the sling-pulleys with the lever 24, or by manual operation of a release lever 25, the trip-member is released and the locking lever falls, so as to clamp the rope and 70 hold the load in position. The general operation thus set forth, of course, involves no novelty and is common in the art.

In accordance with modern practice, it is very desirable on certain occasions to use 75 the carrier in the position shown in Fig. 1, that is arranged for by what is known as direct-draft in which the bight of the rope is parallel to the track. Under other conditions, cross-draft is desired, that is an arrangement with the bight of the rope at 80 right-angles to the track. The present device is designed to afford an interchangeable carrier adapted for both methods of operation. The rope used has an eye 26 at its end, 85 which, when rigged for direct-draft, engages with a hook 27, centrally disposed at the front of the frame. When rigged for cross-draft, the eye is disengaged from the hook 27 and engaged with a hook 28 on the side 90 of the carrier, this hook being so disposed that the bight of the rope is transverse. To accommodate the varying angles of the rope, which necessarily occur, the locking lever 15 has hung upon a pivot a housing 29, in 95 which is mounted the sheave 30 over which the rope passes. The structure is manifestly such that the sheave can swing to an extent sufficient to accommodate the varying angles of the rope. The lever 24, through the medium of which the load trips the device, has its rear end 31 pivoted, this end surrounding 100 the rope and being perforated to admit the rope. By means of the pivot, the rear end of the lever thus likewise accommodates itself 105 to varying angles of the rope.

I realize that considerable variation is possible in the details of the present construction without departing from the spirit thereof, and I do not intend therefore to 110

limit myself thereto, except as pointed out in the following claims, in which my intention is to claim all the novelty inherent in the construction as broadly as the state of 5 the art will permit.

I claim as new and desire to secure by Letters Patent,—

1. In a hay carrier, a frame, a movable member carried by the frame and having 10 means to clamp the rope when lowered, a sheave mounted in said member, and two devices to which the end of the rope may be interchangeably secured, one of said devices being in the longitudinal line of the sheave 15 and the other laterally offset therefrom, for the purpose set forth.

2. In a hay carrier, a frame, a movable member having means to clamp the rope when lowered, a sheave in said member and 20 lying in the longitudinal line of the frame, and two devices to which the end of the rope may be interchangeably secured, one being in the longitudinal line of the sheave and the other laterally offset therefrom, for 25 the purpose set forth.

3. In a hay carrier, a frame, a movable member having means to clamp the rope when lowered, a sheave hung on a pivot running longitudinally of said member and two 30 devices to which the end of the rope may be interchangeably secured, one being in the longitudinal line of the sheave and the other

laterally offset therefrom, for the purpose set forth.

4. In a hay carrier, a frame, a movable member having means to clamp the rope when lowered, a sheave hung on a pivot longitudinally of said member, two devices to which the end of the rope may be interchangeably secured, one being in the longitudinal line of the sheave and the other laterally offset therefrom, 40 a dog to support said member, a lever having connection with said dog, and a pivoted extension on said lever having an eye to engage the rope, for the 45 purpose set forth.

5. In a hay carrier, a frame, a movable member having means to clamp the rope, a sheave hung on a pivot longitudinally of said member, two devices to which the end 50 of the rope may be interchangeably secured, one being in the longitudinal line of the sheave and the other laterally offset therefrom, a dog to support said member, a lever having connection with said dog, and a pivoted extension on said lever having means 55 to engage the rope, for the purpose set forth.

In testimony whereof I have hereunto set my hand this 24th day of October, 1913.

HENRY L. FERRIS.
